United States Patent Office.

DENNIS SAVERY, OF WHEELING, WEST VIRGINIA.

Letters Patent No. 82,354, dated September 22, 1868.

IMPROVED DEVICE FOR HOLDING CUT NAILS WHILE BEING HEADED.

The Schedule referred to in these Letters Patent and making part of the same.

TO ALL WHOM IT MAY CONCERN:

Be it known that I, DENNIS SAVERY, of Wheeling, in the county of Ohio, and State of West Virginia, have invented a new and useful Improvement in Nail-Machines; and I do hereby declare that the following is a full, clear, and exact description thereof, which will enable others skilled in the art to make and use the same, reference being had to the accompanying drawings, forming part of this specification, in which—

Figure 1 is a top view of my improvement.

Figure 2 is a side view of the same, with the anvil-block and griper shown in red, the latter being raised above the nail-block, shown in blue lines.

Similar letters of reference indicate like parts.

The nature of this invention relates to the action of the griping-lever or griper, so called, and operates to retract the griper from contact with the nail-blank after the latter has been headed.

It is always desirable in the operation of nail-machines to have the griper retracted as speedily as possible, and various devices have been used to accomplish this object, but none heretofore have accomplished the retracting in as perfect and instantaneous manner as is done by my invention.

It consists of a U-shaped spring, one end of which is affixed to the cam-end of the griper, and the other clasps or bears against on that side of the cam-shaft which is opposite the griper, thus holding the end of the griper against the shaft, and by its tension, actuating the griper against the shaft instantaneously after the cam has passed the tappet-projection on the griper.

In the drawings—

A is the cam-shaft, B the cam thereon, and C the griping-lever, having a tappet, a.

D is the U-shaped spring, affixed to the end of the griping-lever, as shown, and bearing against the opposite side of the shaft A.

A plate, b, is affixed, by bolts or other suitable means, to the proximate side of the spring at that point, and the said plate bears a leather or other porous pad to soften the action of the spring and return the lubricating-material.

E are the trunnions or vibrating centre of the griper.

As the cam B passes the tappet a, the spring retracts the griper instantaneously, as will be obvious, and at each revolution the cam is lubricated by its passage in contact with the pad e, which is saturated with the lubricating-material.

In fig. 2 the griper a' is shown in red attached to the griping-lever C, and in a raised position above the nail-blank.

Having thus described my invention, I claim as new, and desire to secure by Letters Patent—

The arrangement of the lever C, tappet a, spring D, plate b, pad e, cam B, and shaft A, in the manner and for the purpose specified.

Witnesses:

JOHN MILLER,
PORTER SMITH.

DENNIS SAVERY.
